VENETIAN BLIND TILT-BAR SUPPORT

Jules Nisenson, New York, N. Y., assignor to
 Publix Metal Products, Inc., New York, N. Y.,
 a corporation of New York

Application May 23, 1944, Serial No. 536,993

10 Claims. (Cl. 160—177)

1

This invention relates generally to the Venetian blind art and more particularly to a tilt-bar support therefor.

In accordance with the majority of Venetian blind constructions, the entire blind is carried by a head-bar which is in turn supported by brackets attached to the window frame or other building opening with which the blind is associated. The slats, in an elevated position thereof, are supported by cords which in turn depend from pulleys usually hidden within the head-bar. When the slats are in the lowered position thereof, they are carried by slat supporting tapes and these in turn are connected at the upper ends thereof to the tilt-bar. It is for this reason that the tilt-bar needs to be relatively strong and this condition is increased in the case of those blinds which are relatively wide, that is to say, longitudinally of the tilt-bar. Where the blind is exceptionally wide, in order to preserve the shape and arrangement of the parts, it would be necessary to unduly increase the thickness of the tilt-bar with a consequently unfavorable effect upon the total appearance of the blind. In order to provide additional support for the tilt-bar at a point or points between the terminals thereof, so-called center supports are provided. Such supports movably position the tilt-bar with respect to the head-bar.

Since in many blind constructions it is desirable that the tilt-bar be removable as a unit from the brackets and the head-bar, it is desirable that such tilt-bar center supports be likewise detachably connectable.

It is, therefore, among the principal objects of the present invention to provide Venetian blind tilt-bar center support construction which is quickly and easily attached to the tilt-bar and to the head-bar.

Another object herein lies in the provision of structure of the class described, which is quickly and easily detachable. Such detachability facilitates the removal of the tilt-bar from the head-bar so that the blind may be cleaned, adjusted or refurbished.

Another object herein lies in the provision of Venetian blind tilt-bar center support construction, which enables the tilt-bar to be rotated axially about the end pins thereof. It is desirable that such rotation may occur without binding or any undue application so that the Venetian blind may be tilted in the usual manner without excessive effort being required.

Another object herein lies in the provision of a Venetian blind tilt-bar center supporting de-

vice, which is of simple construction, largely metal stampings, so that the same may be manufactured in large scale production at low cost and have a consequent wide sale and use.

These objects and other incidental ends and parts will more fully appear in the progress of this disclosure and be pointed out in the appended claims.

In the drawings in which similar reference characters designate corresponding parts throughout the several views:

Figure 1 is a fragmentary front revisional view partly in section, showing a first embodiment of the invention.

Figure 2 is an enlarged vertical sectional view as seen from the plane 2—2 on Figure 1.

Figure 3 is a horizontal sectional view seen from the plane 3—3 on Figure 2.

Figure 4 is a view in perspective of the tilt-bar center support as removed from the head-bar bracket therefor.

Figure 5 is a view in perspective showing a second embodiment of the invention.

In accordance with the invention the device 10 generally indicated by reference character 10, is associated with a head-bar 11 and a tilt-bar 12. The head-bar 11 may be of the usual construction having tilt-bar end support brackets 13, only one of which is shown in the drawing. The tilt-bar 12 may also be of standard construction and may be provided with end pins 14 (only one of which is shown) which are adapted to be rotatably journaled in the brackets 13. Any desired number of slats 15 (only one of which is shown) may be carried by the tilt-bar 12, by the slat supporting tapes 16 (only one shown).

While the device 10 is referred to in the specification and claims as a tilt-bar center support, it will be understood that the word "center" is used only loosely as it is in the trade, and that the support 10 may be located at any point or points desired between the actual ends corresponding to the end 11 of the tilt-bar 12.

The device 10 includes two separable parts, a head-bar element 18 and a tilt-bar element 19.

The head-bar element 18 is preferably formed of a rectangular plate and includes a central tilt-bar element engaging portion and a pair of oppositely disposed attaching flanges (21 and 22). The element 18, as best seen in Figures 1 and 2, has the central tilt-bar element engaging portion 20 disposed at a level below that of the flanges 21 and 22, so that the upper surface 23 may be spaced from the undersurface 24 of the tilt-bar 12, a distance substantially equal to or

greater than the effective thickness of the laterally extending projections 25 and 26. The portion 20 is provided with an indentation or open ended slot 27, which extends inwardly from the forward edge 28 of the element 18. The width of the portion 20 (longitudinally of the element 18) is preferably equal to or slightly greater than the greatest distance between the terminals of the projections 25 and 26. The flanges 21 and 22 are preferably provided with orifices which may be penetrated by screws 29 and 30 which serve to secure the element 18 to the undersurface 31 of the head-bar 11.

The tilt-bar element 19 is best seen in Figure 4 and includes a tilt-bar supporting plate 32. The plate 32 is preferably rectangular in shape and has at the side edges 33 and 34 upstanding tilt-bar penetrating prongs 35-38, inclusive. The prongs 35 and 37 and the prongs 36 and 38 are oppositely disposed in such manner that their angularly disposed edges 45, 46, 47 and 48 incline toward each other as shown on the drawing. The co-action of said angularly disposed edges 45-48, inclusive, is such that when the plate 32 is driven against the undersurface 39 of the tilt-bar 12, said plate will be prevented from shifting laterally out of the position it occupied when the tips or points of the prongs 35-38 were placed against the undersurface of the tilt-bar. The central portion of the plate 32 is provided with a pair of spaced and parallel slots 40 and 41 which are upwardly penetrated by a U-shaped trunnioning member 42. The cross piece 43 of the member 42 carries upon the upper surface thereof, the undersurface 44 of the plate 32. The upper ends of the arms 49 and 50 of the member 42 are provided with co-axially arranged orifices within which the axle 52 is trunnioned. The axle 52 is provided at the terminals thereof with suitable enlargements and may in fact take the form of a commercially available and well known elongated rivet.

The tilt-bar element 19 also includes a suspension member 53. The member 53 may be blanked from a single piece of strip stock and at the upper end thereof may be slit to provide the material from which the two projections 25 and 26 may be formed by bending them each through 90° in opposite directions so that they are parallel with each other and perpendicular to the body of the suspension member 53. The suspension member 53 at the lower end thereof is provided with an orifice penetrated by the axle 52.

In use the tilt-bar 12 is provided with an orifice 54 of a size sufficient to permit the insertion therein of the arms 49 and 50 of the U-shaped trunnioning member 42, and the suspension member 53, as well as the arms 49 and 50 are passed upwardly through the orifice 54 and the tilt-bar element 19 is secured in place by forcing the plate 32 against the undersurface 39 until the prongs 35-38, inclusive, are fully seated. Obviously, as has been mentioned above, the orifice 54 may be located at any desired point along the tilt-bar 12, but is preferably so located that the axle 52 will be in co-axial alignment with the pins 14 (only one pin 14 is shown). The position of the axle 52 is, of course, correlated to the thickness of the tilt-bar with which the device is to be used. The head-bar element 18 is secured to the undersurface 31 of the head-bar 11 with the slot 27 thereof so disposed that when the suspension member 53 is vertically disposed, the projections 25 and 26 may be fully

seated thereabove and the body portion of the member 53 may contact the inner end of the slot 27 or substantially contact the same. In this position a portion of the weight of the tilt-bar is carried by the plate 32 through the U-shaped member 42, the axle 52, the member 53, the projections 25 and 26, the element 18 and the screws 29 and 30 to the head-bar 11. The tilt-bar 12 may freely rotate about the pins 14 and the axle 52, being limited only by the abutment of the edges 55 and 56 against the lowermost surfaces of the routed grooves 57, 58.

By virtue of the fact that the slot 27 opens forwardly, that is to say, toward the front surface 59 of the head-bar 11, the tilt-bar together with the attached structure, may be removed both from the element 18 and the brackets 13 by a forward sliding motion. Suitable locking devices, well known in the art and not shown in the drawings, may be used to prevent the undesired or accidental displacement of the pin 14 from the brackets 13.

Turning now to the second embodiment of the invention illustrated in Figure 5 of the accompanying drawings, for the purpose of avoiding needless repetition, parts corresponding to those of the first embodiment are given the same reference characters with the prefix "1."

The second embodiment differs from the first embodiment principally in the arrangement of the head-bar elements 118 being so disposed that its greatest length lies transversely of the head-bar 111. This produces the effect of having the opening of the slot 127 disposed in such manner that the projections 125 and 126 make it necessary to insert the suspension element 153 by a movement longitudinally of the head-bar 111. The projections 125 and 126 may be fabricated so that they form a T-shape end on the suspension member 153. The projections 125 and 126 may lie in the same plane as the suspension member 153 or they may be rotated through 90° so that the flats of the wider portions thereof may lie upon the upper surface of the central tilt-bar element engaging portion 120.

It may thus be seen that I have provided a novel and useful Venetian blind tilt-bar support which is of simple and foolproof construction and which may be installed with a minimum of skill and effort. After installation it provides proper support for the tilt-bar while providing for proper rotation of the tilt-bar. By virtue of the fact that the U-shaped member 43 may be loosely disposed in oversized slots 40 and 41, said slots being closed at both ends and therefore elongated orifices, if the plate 32 or head-bar element 18 are improperly positioned within limited values of disalignment, with a certain amount of looseness in the parts, they may articulate slightly to accommodate such disalignment and yet provide satisfactory operation. Thus, since the suspension member 53 is rotatable about one axis and the U-shaped member 42 is shiftable about an axis disposed substantially perpendicularly thereto but in a parallel plane, the parts may shift to accommodate disalignment of a limited degree.

I wish it to be understood that I do not desire to be limited to the exact details of construction shown, for obvious modifications will occur to a person skilled in the art.

I claim:

1. A Venetian blind tilt-bar support for use with a head-bar and a tilt-bar, said support comprising: a head-bar element adapted to be secured to said head-bar and having a slot, said ele-

ment being spaced from the head-bar at and along said slot; a tilt-bar element adapted to be secured to said tilt-bar and including a tilt-bar supporting plate and a suspension member pivotally associated with said plate; said suspension member being adapted to penetrate said slot, said suspension member at the upper end thereof having an enlargement greater in effective width than the width of said slot, whereby said suspension member is insertable within said slot longitudinally of the slot, but is prevented from being pulled vertically downward through the slot by said enlargement.

2. A Venetian blind tilt-bar support for use with a head-bar and a tilt-bar, said support comprising: a head-bar element adapted to be secured to said head-bar; a tilt-bar element adapted to be secured to said tilt-bar and including a tilt-bar supporting plate, a U-shaped member secured to said tilt-bar supporting plate and a suspension member pivotally associated with said U-shaped member; and means to detachably connect said suspension member to said head-bar element.

3. A Venetian blind tilt-bar support for use with a head-bar and a tilt-bar, said support comprising: a tilt-bar element adapted to be secured to said tilt-bar and including a tilt-bar supporting plate, a U-shaped member secured to said tilt-bar supporting plate and extending into said tilt-bar and a suspension member pivotally associated with said U-shaped member; and means to detachably connect said suspension member to said head-bar element.

4. In a Venetian blind construction, including a tilt-bar and a head-bar, means to suspend the tilt-bar from the head-bar, comprising a head-bar element in the form of a first plate having a depression with an open ended slot therein; a tilt-bar element having a second plate connected to the undersurface of the tilt-bar; said tilt-bar element including a member penetrating the second plate and a suspension member pivotally connected to the penetrating member; said suspension member being insertable within said slot and having an enlargement on the end thereof adapted to lie within the said depression in the first plate when the suspension member is engaged within the said slot.

5. In a Venetian blind construction, including a tilt-bar and a head-bar, means to suspend the tilt-bar from the head-bar, comprising a head-bar element in the form of a first plate having a depression with an open ended slot therein; a tilt-bar element having a second plate connected to the undersurface of the tilt-bar; said tilt-bar element including a suspension member penetrating the tilt-bar and pivotally connected to the second plate; said suspension member being insertable within said slot and having an enlargement on the end thereof adapted to lie within the said depression in the first plate when the suspension member is engaged within the said slot.

6. A Venetian blind tilt-bar support for use with a head-bar and a tilt-bar, said support comprising: a head-bar element adapted to be secured to said head-bar; a unitary tilt-bar element adapted to be secured to said tilt-bar and including a tilt-bar supporting plate having a pair of integral prongs each having an angularly disposed edge, said prongs being adapted to penetrate said tilt-bar, and a suspension member pivotally connected to said plate, said angularly disposed edges being oppositely arranged and inclined toward each other in a direction away from the tilt-bar supporting plate; and means to detachably connect said suspension member to said head-bar element.

7. A device as claimed in claim 1 in which the enlargement on the free end of the suspension member is T-shaped.

8. A device as claimed in claim 1 in which the enlargement on the free end of the suspension member is formed by said free end being bifurcated with the two projections oppositely bent through substantially 90°.

9. Venetian blind construction comprising: a head-bar; a tilt-bar having an orifice therein; a head-bar element secured to the head-bar; a tilt-bar element including a tilt-bar supporting plate and a suspension member pivotally connected to said plate and penetrating said orifice; and means to detachably connect said suspension member to said head-bar element.

10. Venetian blind construction comprising: a head-bar; an elongated continuous tilt-bar with top and bottom walls, said tilt-bar having an orifice extending between said top and bottom walls and a pair of slots extending laterally outward, transversely of the tilt-bar, from said orifice, said slots being in the top wall and having their lowermost portions spaced a substantial distance above the bottom wall; a head-bar element secured to the head-bar; a tilt-bar element including a tilt-bar supporting plate and a suspension member pivotally connected to said plate and penetrating said orifice; and means to detachably connect said suspension member to said head-bar element; said suspension member entering one of said slots as the tilt-bar approaches its extreme tilted position in one direction and entering the other of said slots as the tilt-bar approaches its extreme tilted position in the other direction.
